CLAIM

The ornamental design for a mouse pad in the shape of a basketball jersey, as shown and described herein.

DESCRIPTION

FIG. 1 is a perspective view of a mouse pad in the shape of a basketball jersey according to the present design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The elements illustrated in dashed lines in the accompanying drawings are considered environmental and do not form a part of the claimed design.
